CLAIM

The ornamental design for a pendant, as shown and described.

DESCRIPTION

FIG. 1 is a front view of a pendant showing my new design; FIG. 2 is a rear view thereof; FIG. 3 is a right side view thereof; FIG. 4 is a left side view thereof; FIG. 5 is a top view thereof; FIG. 6 is a bottom view thereof; FIG. 7 is a front perspective view thereof; and, FIG. 8 is a front view of the pendant of FIGS. 1-7 showing a stone region in a changed state of appearance relative to FIGS. 1-7.

The stippling shown on the stone region in FIG. 8 represents a contrast of appearance with respect to remaining stones and the change of state is affected when the pendant is exposed to ultraviolet light.
